UNITED STATES PATENT OFFICE.

WILLIS E. HALL, OF NEW YORK, N. Y., ASSIGNOR OF ONE-HALF TO CHARLES A. TATUM, OF NEW YORK, N. Y.

APPARATUS FOR DRYING BY COMPRESSED AIR.

1,091,215.

Specification of Letters Patent. Patented Mar. 24, 1914.

Application filed March 22, 1905. Serial No. 251,388.

To all whom it may concern:

Be it known that I, WILLIS E. HALL, a citizen of the United States, and a resident of the borough of Manhattan, city, county, and State of New York, have invented certain new and useful Improvements in Apparatus for Drying by Compressed Air, of which the following is a specification.

My invention relates to drying various materials by the aid of a current of compressed gas, or gaseous fluid generally air.

With ordinary drying processes in which a draft of air is employed, considerable difficulty is often experienced on account of the moisture contained in the atmosphere, particularly as the degree of humidity is subject to wide fluctuations.

The object of my present invention is to deprive the air of its moisture in an economic and efficient manner, so that a current of dry air may be directed against or about the substance or article to be treated. In addition to this, I provide means whereby the air may be heated or cooled so as to give it the temperature most suitable in each individual case.

Referring to the accompanying drawing, Figure 1 is a sectional partly diagrammatic view of an apparatus or plant embodying my invention; Fig. 2 is a sectional view of another arrangement of my device; Fig. 3 is an elevation of still another arrangement and Fig. 4 shows a slightly different arrangement of the parts shown in Fig. 2.

The apparatus shown in Fig. 1 comprises a suitable engine A connected with an air compressor B, of any approved construction. The compressed air passes through a pipe C, to the chamber D, of a separator or cooler E, containing a pipe system F, through which water circulates, the air passing around the pipes. The compression and cooling of the air cause the moisture contained therein to separate and settle at the bottom, whence it can be removed by opening a drain cock G. In some cases the air after leaving the cooler and passing through a reducing valve H, will have the proper cool temperature. In other cases, however, when heating of the air is desirable the air will pass from the cooler E, through the reducing valve H, to the temperature-variator or heater I, which may be of the same construction as the cooler. Here a heating

medium flows through pipes J, and gives up heat to the gas cooled by expansion, said gas flowing around the pipes. The dry air thus obtained either hot or cold as may be best for the particular purpose in view may pass through another reducing valve K to the place of use, for instance to a distributing pipe L, having lateral openings for the discharge of the regulated compressed air and arranged within a box M which has a series of perforations in its top M' adjacent to a run N, of the material to be dried. This top piece M' is preferably slidably mounted in any suitable manner on the box M, so that it may be removed and cleaned when desired and any drippings be thrown out. A deflector O, may be interposed between the pipe L and the top M' to cause the air to issue uniformly at all points. The perforations reduce or muffle the velocity of the air and divide it into small jets thus enabling it to better absorb moisture and equalize the pressure.

Referring now to the arrangement shown in Fig. 2, a represents a pipe which is connected at one end with an air compressor, and at the other end with a variator b having a series of pipes c around which a heating or cooling medium is circulated. In the arrangement shown, the circulating medium would be of a cooling nature, said cooling medium entering the variator b through the inlet pipe d. At the end opposite to the one at which the compressed air enters the variator b, the said variator is connected with a separator comprising a chamber e having an outlet f. Partitions g in the separator serve to deflect the current of air which passes from the variator through the pipe b' in the direction indicated by the arrows and baffle plates h are provided in the separator so that the water contained in the air may be easily separated therefrom. After separation from the air the water may be drained off through the outlet f. From the chamber e, the air passes over the baffle plates h before mentioned, through openings i and j, into a chamber k which surrounds the chamber e. From the chamber k the air passes through openings l to the place of usage.

When it is desired to have the final temperature of the air higher than the initial temperature of the free air before compres-

sion, the variator and separator will be transposed, and thus the compressed air will be caused to travel first through the separator and then through the variator; that is, 5 the pipe *a* conveying the air from the compressor will be connected directly with the separator at *b'*, and the air passing out of the separator at *m* will be led to the same end of the variator which in Fig. 2 is connected with the pipe *a*. The outlet of the 10 variator will be connected with the place of use. In the variator a heating medium will be circulated around the pipes *c*, instead of a cooling medium. This altered arrangement is illustrated in Fig. 4.

When extreme dryness is not required and a temperature of practically the air before compression is desired, the arrangement shown in Fig. 3 may be used. In this instance, the compressed air passes from the 20 compressor 1 through a pipe 2 into the separator 3 which may be of the same general character and operate in the same manner as the separator described with respect to and 25 shown in Fig. 2. From the separator 3 the air may pass through a reducing valve 4 to the drier or to the point where it is desired to use said air, either under compression or at practically atmospheric pressure.

30 By my invention I provide means for drying substances and articles of various kinds in an efficient manner owing to the removal of a large amount of moisture from the air.

The apparatus is valuable in the drying of 35 fabrics and matches, for example, and the regulation of pressure depends as does the regulation of temperature on the particular substance to be treated.

The apparatus is not affected by changes 40 in the humidity of the atmosphere, and constant conditions may be preserved by a proper regulation of the apparatus.

A very important feature of my invention is the location of a reducing valve between 45 the compressor and the discharge device. I give the term "reducing valve" the meaning generally given in the art, that is, I designate by such term a valve which will maintain a particular determined pressure on the 50 discharge side irrespective of fluctuations on the supply side. It will be obvious that the compressor will cause a pulsating effect in the piping on the supply side of the reducing valve and unless I employ a reducing valve having these characteristics, that is, 55 the property of automatically maintaining a constant pressure on the discharge side, a pulsating jet would be delivered at the discharge device, such as the pipe *L*. A uniform action would be impossible with such a pulsating jet in view of the fact that each material to be dried requires for the securing 60 of the best results a definite velocity of the drying medium. It is well known that reducing valves as ordinarily made are pro-

vided with an adjusting device, whereby the discharge pressure may be altered within certain limits, but of course, the discharge pressure remains constant as long as the adjustment is not changed. With my invention therefore I would adjust the reducing valve to the particular pressure which by experience I know to be best for the particular material to be dried and then I would be certain that during the entire process the 70 air would be discharged at the particular velocity best suited for the rapid drying of that material.

Various modifications may be made without departing from the nature of my invention.

I claim as my invention:

1. An apparatus for drying by compressed gaseous fluids, comprising a fluid compressor, a moisture separator for eliminating moisture from said fluid, a chamber for collecting such fluid after said elimination has taken place, a means for bringing the fluid to a predetermined temperature and a controlling device arranged to permit the ejection of said compressed dried fluid at a predetermined pressure, said compressor, moisture separator, chamber, means and controlling device being in communication with each other.

2. An apparatus for drying by compressed gaseous fluids, comprising a fluid compressor, a moisture separator for eliminating moisture from said fluid, a chamber for collecting such fluid after said elimination has taken place; a controlling device arranged to permit the ejection of said compressed dried fluid at a predetermined pressure, said compressor, moisture separator, chamber and controlling device being in communication with each other and a discharge device connected with and located beyond said controlling device for directing the discharge of said dried fluid under the predetermined pressure.

3. An apparatus for drying by compressed gaseous fluids, comprising a fluid compressor, a moisture separator for eliminating moisture from said fluid, a chamber for collecting such fluid after said elimination has taken place, a means for bringing the fluid to a predetermined temperature, a controlling device arranged to permit the ejection of said compressed dried fluid at a predetermined pressure, said compressor, moisture separator, chamber, means and controlling device being in communication with each other, and a discharge device connected with and located beyond said controlling device for directing the discharge of said dried fluid under the predetermined pressure.

4. An apparatus for drying by compressed gaseous fluids, comprising a fluid compressor, a discharge device through which

the dry gas is arranged to issue, a reducing valve, a moisture separator, and a temperature variator connected in series and all three interposed in the connection between the compressor and the discharge device, said reducing valve opposing a constant resistance to the passage beyond said valve, of the gas coming from the compressor.

19 5. An apparatus for drying by compressed gaseous fluids, comprising a fluid compressor, a moisture separator connected to receive the fluid from the compressor, a box having perforations to discharge the fluid against the material to be treated, a conducting means arranged to receive the fluid from the separator and having its discharge end within said box, a reducing valve located in said conducting means, and a deflector be-

tween the discharge end of said conducting means and the perforations of the box.

6. An apparatus for drying by compressed gaseous fluids, comprising a fluid compressor, a moisture separator connected to receive the fluid from the compressor, a box 25 for receiving the fluid and the material to be treated, a conducting means arranged to receive the fluid from the separator and having its discharge end within said box and a reducing valve located in said conducting means arranged to insure the discharge of the dry fluid at a predetermined constant pressure.
